UNITED STATES PATENT OFFICE.

WILLIAM B. JUPP, OF NEW YORK, N. Y., ASSIGNOR TO INTERNATIONAL MOTOR COMPANY, OF NEW YORK, N. Y., A CORPORATION OF DELAWARE.

CAR-BODY CONSTRUCTION.

Application filed November 26, 1927. Serial No. 235,917.

The present invention relates to body constructions for vehicles and deals particularly with the application of new features of construction to rail cars. Where a car of this character is to be driven by electric power generated within itself, the disposition of the driving units may be made to conform with that of the usual traction type of car but the power generating units must be carried within the body. This gives rise to problems which are not confronted where the power comes from an external source, having to do with the mounting of the units so as to provide the maximum amount of room for passengers and baggage and yet conform to the best railway practice for convenience and accessibility.

This invention has for an object the construction of a rail car with power generating units and auxiliary apparatus so disposed that a through-aisle exists from one end of the car to the other, thereby insuring free access to all portions of the body and unimpeded passage through the car. Where cars are coupled in a train, this feature is of particular importance, since it is in accord with general railway practice. The manner in which the units are mounted in the present construction provides the above features.

A further object of the invention is to provide an improved mounting for the exhaust stacks, radiators and other auxiliary apparatus of a power plant including an internal combustion engine. These elements are positioned to agree with the general principles outlined above, thus preserving the through-aisle character of construction.

Reference will now be had to the accompanying drawings for a further and more detailed description of the invention. In the drawings:

Figure 1 is a view in horizontal section taken on line 1—1 of Figure 2 and looking in the direction of the arrows, showing a car body construction embodying the present invention.

Figure 2 is a view in side elevation showing the improved body construction.

Figure 3 is an end elevation of the improved car viewed from the left of Figure 2.

In the drawings, there is shown a car body *a* provided with seats *b* and power generating units *c*. The body may be divided into a vestibule *d*, passenger compartment *n*,

smoking compartment *e*, baggage room *f* and engine room *g* by means of the respective partitions *d'*, *e'*, *f'* and *g'*. Of course, in connection with the subdivision of the body into compartments, it will be apparent that any desired plan may be followed to suit varying conditions, the present invention confining itself to the proper adaptation of such compartments to a through-aisle construction as described hereinafter.

Extending from end to end of the car through the passenger and smoking compartments, is a center aisle *h*, the continuity of which through the respective compartments is provided by means of aligned doors *d²*, *e²*, *f²* and *g²* in the respective partitions. When cars are to be connected in tandem, end doors *i* permit the through-aisles of the respective cars to be continued throughout the length of the train, and in this manner, communication from end to end is established.

A control booth *j* and a lavatory *j'* are formed in the vestibule *d* on either side of the aisle section and at the other end of the car, a second control booth *k* may be provided to include one of the power units *c*. It will be observed that the power units *c*, within the engine room *g*, are disposed upon either side of the through-aisle section *h*, doors *g³* being provided in the partition *g'* to permit the power units *c* to be removed readily.

As part of the auxiliary apparatus for the power plants which, in the illustrated embodiment, are gas-electric roof radiators *l* as part of the cooling system of the engine, and stacks *m* for exhaust, are provided. The roof radiators and stacks are mounted at opposite sides of the car for the respective power units, and in this manner the through-aisle section *h* in the engine room *g* remains unobstructed. The auxiliary apparatus for each unit, being mounted at the side of the aisle section, is more readily accessible and in no way impedes free passage therethrough.

The above construction treats the space in the car at opposite sides of the aisle as entirely independent sections with no superstructure extending across the aisle section to impede movement therein and a greatly improved body construction with maximum accessibility for the units, results.

I claim as my invention:

1. A car construction of the character described comprising a body, a plurality of power plants carried therein, a central aisle section through the car, center doors at either end of the car whereby access may be had to the car through the ends thereof, and means to mount the power plants to preserve the continuity of the aisle through the car and doors from end to end thereof.
2. A car construction of the character described comprising a body, a plurality of power plants carried therein, exhaust stacks for the respective power plants, an aisle section, and means to mount the power plants and stacks at opposite sides of the aisle sec-

tion to preserve the continuity of the aisle through the car from end to end thereof.

3. A car construction of the character described comprising a body, a plurality of power plants carried therein, exhaust stacks and cooling means for the respective power plants, a center aisle section, and means to mount the respective power plants, stacks and cooling means at opposite sides of the aisle section to preserve the continuity of the aisle through the car from end to end thereof.

This specification signed this 22nd day of November A. D. 1927.

WILLIAM B. JUPP.
